UNITED STATES PATENT OFFICE.

JOHN JACKSON, OF CLINTON, IOWA.

PAIL.

1,111,589.

Specification of Letters Patent. Patented Sept. 22, 1914.

Application filed January 13, 1913. Serial No. 741,872.

To all whom it may concern:

Be it known that I, JOHN JACKSON, a citizen of the United States, residing at Clinton, in the county of Clinton and State of Iowa, have invented new and useful Improvements in Pails, of which the following is a specification.

This invention relates to improvements in pails for use in gathering fruit, and of that 10 general type which includes an open ended body portion and a displaceable bottom which may be manipulated to provide for the discharge of fruit therethrough and is provided for the purpose of preventing the 15 fruit from becoming bruised or otherwise injured when it is discharged from the pail.

According to the present invention, the improved pail comprehends a rigid open ended body part, of suitable material and 20 an open ended tubular or cylindrical sack which is secured at the lower end of the body part, preferably for detachment therefrom, and is normally folded to constitute a flexible bottom for the body part, being 25 held in such relation by one or more straps which it carries and which have their free ends constructed for detachable engagement with fastening devices arranged at the side of the pail.

30 The object of the invention as above outlined is a construction of very simple and inexpensive nature, allowing the utilization of the full capacity of the pail, in which the bottom may be folded or extended 35 quickly and with facility, and in which the bottom may be quickly and readily removed for the purposes of substitution, renewal, or repairs.

An embodiment of the invention is illustrated in the accompanying drawings, 40 wherein:

Figure 1 is an elevation of a preferred form of the improved pail, the sack being in extended relation; Fig. 2 is a view similar 45 to Fig. 1, but at right angles thereto; Fig. 3 is a detail sectional view showing the sack in folded relation; Fig. 4 is an elevation of a slightly modified construction, the sack being folded to form a bottom; Fig. 5 is a 50 vertical central sectional view of the modified construction, the sack being open to provide for the discharge of the contents of the pail; and Fig. 6 is a detail sectional view 55 of the modified construction showing the manner of securing the sack in folded relation.

Similar characters of reference designate corresponding parts throughout the several views.

The rigid open ended body of the pail is 60 indicated generally by the numeral 1, and may be conveniently made of metal. It preferably, though not necessarily, has the shape of a frustum of a cone, and in the embodiment shown, is provided at its lower 65 end with a bead or equivalent enlargement 2.

An open ended tubular or cylindrical sack 3, of canvas or other flexible material suitable for the purpose, is secured to the lower 70 portion of the body 1, preferably for detachment therefrom. A convenient arrangement for securing the sack 3 to the lower portion of the body 1 comprises a clamping ring 4 which fits over the upper 75 portion of said sack and frictionally clamps the same against the wall of the body 1, the ring 4 being positioned between, and held in place by, the bead 2 aforesaid, and a wire ring 5 secured in a seam at the upper end of 80 the sack 3. With the arrangement thus far described, the ring 4 is fitted immediately under the ring 5, and the sack 3 is then slipped over the smaller end of the body 1, being drawn toward the larger end of said 85 body until the ring 4 comes substantially against the bead 2 and arrests further movement of said sack.

The sack 3 is to be folded in any convenient manner to close the lower end of the 90 body 1, and to thereby constitute the bottom of the pail, as shown in Fig. 3. For the purpose of securing the sack in this folded relation, means is employed which includes a pair of straps 6, each having an end thereof 95 secured to the sack somewhat adjacent the outer end of the latter, preferably permanently and by stitching. The straps 6 are preferably arranged in diverging relation and are of a length to project beyond the 100 bottom of the pail, and in the embodiment shown, have their free end portions provided with eyelets 7 through which are engaged hooks 8, the latter, in connection with the straps 6, constituting the means for securing the sack 3 in folded relation. The 105 hooks 8 are arranged at the side of the pail opposite to the line of attachment of the straps 6 to the sack 3, and are preferably permanently secured to the pail, being located a suitable distance above the ring 4 110 to enable the ready removal of the latter.

To discharge the contents of the pail, all that is required is to disengage the ends of the straps 6 from the hooks 8, so as to allow the sack 3 to extend and to permit the contents of the pail to drop therethrough into any suitable receptacle that may be provided. The sack 3 may be entirely dissociated from the body 1 with great facility, as is obvious.

The modified construction, shown in Figs. 4, 5, and 6, is the same in its general principles as the construction already described. In this case, in lieu of the two straps 6, shown in the preferred construction, a single strap 6^a is employed. The strap 6^a has one end secured to the sack somewhat adjacent the inner end thereof and preferably by stitching, and is of a length to extend wholly across and beyond the bottom of the pail. At its free end the strap 6^a is provided with eyelets 7^a through which are engaged hooks 8^a, constituting the means for securing the sack 3 in folded relation. The hooks 8^a are, of course, arranged at the side of the pail opposite to the line of attachment of the strap 6^a, and are of substantial S-shape, whereby they may be hooked over the ring 5 with their back portions held by the ring 4 in relatively secure frictional engagement between the wall of the body 1 and the upper portion of the sack 3.

The arrangement of hooks 8^a shown in connection with the modified construction is obviously equally applicable to the construc-

tion shown in Fig. 1, in lieu of the hooks 8. In such event, however, the projecting ends of the straps 6 would be somewhat shorter, since the hooks 8^a would be located nearer to the lower end of the body 1 than the hooks 8.

Having fully described my invention, I claim:

A pail of the type set forth, comprising a rigid open ended body shaped like a conic frustum and having its greatest diameter at its lower end, a tubular open ended sack, the rigid body having a circumscribing bead at its lower end and the sack having a ring at its upper end formed to surround the body above the bead, a clamping ring frictionally engaging the upper end of the sack and surrounding the body between the first named ring and the bead, the clamping ring being removable from said body by upward displacement relatively thereto, the sack being adapted to be folded across the lower end of the body to form a bottom thereof, hooks arranged at one side of the body, and a strap having an end secured to the sack and having a free end constructed for engagement with said hooks to hold the sack in folded relation.

In testimony whereof I have hereunto set my hand in presence of two subscribing witnesses.

JOHN JACKSON.
